UNITED STATES PATENT OFFICE.

WILLIAM A. READE, OF CLEVELAND, OHIO, ASSIGNOR TO THE LUDLOW TYPOGRAPH COMPANY, OF CLEVELAND, OHIO, A CORPORATION OF MAINE.

TYPOGRAPH MECHANISM.

1,207,622.

Specification of Letters Patent.

Patented Dec. 5, 1916.

Application filed May 19, 1911, Serial No. 628,260. Renewed February 28, 1916. Serial No. 81,058.

To all whom it may concern:

Be it known that I, WILLIAM A. READE, a citizen of the United States, and a resident of Cleveland, county of Cuyahoga, and 5 State of Ohio, have invented a new and useful Improvement in Typograph Mechanism, of which the following is a specification, the principle of the invention being herein explained and the best mode in which I have 10 contemplated applying that principle, so as to distinguish it from other inventions.

The present invention relates to a modified form of mechanism for casting slugs, or lines of type, wherein the characters shall 15 be inclined, as in italics. Heretofore this has only been possible by distorting the characters from their correct and accepted forms, since it is obviously out of the question to employ overlapping matrices in typograph work, which is the way italic type 20 require to be formed for regular printing. Italic type in larger sizes has furthermore become more or less popular in the setting up of display advertisements in newspapers, 25 hand-bills, and the like, and here, perhaps, the distortion necessary in the prevailing practice becomes objectionably noticeable. In its illustrated form, the present invention 30 accordingly shows the use of italic characters of such larger size. The general features of construction exemplified in the matrix bars for casting such larger characters, as well as the improved holding and positioning device for assembling such matrix bars are 35 not presented as a part of the present invention, such holding device, in particular, forming the subject matter of a co-pending application, filed May 22, 1911, Ser. No. 628,649.

40 The object of the present invention, then, is to provide a special form of matrix bar and to adapt the aforesaid device for the kind of work in hand, and to the accomplishment of this and related ends, said invention 45 consists of the means hereinafter fully described and particularly pointed out in the claims.

The annexed drawing and the following description set forth in detail certain mechanism embodying the invention, such disclosed means constituting, however, but one

of various mechanical forms in which the principle of the invention may be used.

In said annexed drawing:—Figure 1 is a plan view of a holder of the construction 55 utilized in carrying on the present invention; Fig. 2 is a transverse section of said holder and associated parts taken on the line 2—2, Fig. 1; while Fig. 3 illustrates, apart from the holder, one of the matrix 60 bearing members of novel design which form a feature of the invention; and Fig. 4 shows a modification in construction.

The holding device, in the preferred form of construction illustrated, comprises as in 65 the co-pending application referred to, a solid metallic frame 1 of box-like form, open on one face. One of the sides 2 of said frame is furthermore movable so as to lay wide open the interior of the box, in 70 which condition the latter is adapted to readily receive the matrix bars or members 3. These are in general of well known form resembling those employed in various kinds of typograph machines, each having 75 but a limited number of characters 4, only one being shown. Said members are of such a depth as to extend just a trifle above the open face of the holder and are furthermore notched at their respective ends to engage 80 corresponding projections, or seats 5 and 6 on the fixed and movable sides of the holder. Such movable side is pivotally attached to the base of the holder and a spring 7, connected at opposite ends to the side and base, 85 is adapted to retain the same in either open or closed position, as will be readily understood. The matrix-bearing members or bars, however, (see Figs. 1 and 3) differ from bars of this kind as heretofore constructed, in that they themselves slant at 90 an angle to the line upon which they are designed to be assembled or composed, such angle being the same as that of the characters which, as previously indicated, are 95 italics. In other words, the characters are disposed parallel with the sides of the members and the ends of the latter are cut off at an angle complementary to that which the characters make to a horizontal line. 100 The appearance of the members when assembled in the holder is clearly shown in

Fig. 1, where in addition are shown the means whereby they are clamped in place after being thus assembled. Such means comprise angular blocks 8, 8 secured in the 5 respective ends of the holder, one of such blocks being slidably mounted therein and a screw 9 in the adjacent end of the holder being rotatably connected with said slideable block so as to be adapted to press the same 10 against the adjacent member 3. The other block may, of course, be formed integral if desired, with the holder, but by having the same separate, the holder is adapted to receive ordinary square matrix-bearing members 15 equally as well as such inclined, "italic" matrices.

In the casting operation, the holder is inverted over the mold box 10 so as to bring the characters on the assembled members 20 over the casting slot 11 in said mold. This slot (see Fig. 2) has a square, enlarged portion for forming an off-set or enlarged body portion in the completed slug, in order to accommodate the matrices which, as have 25 been indicated, are of larger size than ordinary type. To facilitate the proper location and alinement of such assembled matrices, an abutment 12 is provided on the table top 13, or equivalent support, upon which the 30 holder rests, just as in the co-pending application: also a suitable clamping member 14 is adapted to be pressed down upon the inverted bottom of the holder, in order to secure the matrix bars solidly against the upper face of the mold box.

By the foregoing construction, very simple, yet efficient, means are provided for the casting of slugs with characters of the special form under consideration. In fact 40 such slugs may be made just as quickly and rapidly as slugs of ordinary characters of corresponding size, for the manufacture of which the mechanism in hand is in general adapted. The slugs will obviously be of 45 square outline and so susceptible of being assembled in the same fashion as though the characters borne by them were likewise square.

It will be understood that the arrangement and form of the matrix bars, as well as the construction of the holder, will be substantially the same where the characters are of smaller size than the display characters illustrated in Figs. 1, 2 and 3. Accordingly 50 in Fig. 4, where such smaller characters are exhibited, the only modification in the particulars just referred to is in the matter of size. There is illustrated in said Fig. 4, however, a different arrangement of the 55 matrix bars, viz., the combination in the one holder 1 of both slant bars 15 and straight bars 16. Angular blocks 17, corresponding with end blocks 8 of construction first described, are interposed between the

body of slant, italic-bearing matrix bars, 65 and the regular bars. Any space at the ends of the composite body of bars may then be filled up with rectangular bars or blocks, and all clamped in place as before. It, of course, need scarcely be explained that not 70 only may such body of bars be thus shifted in the construction of Fig. 4, in order to center or otherwise dispose them in the holder as may be desired, but that in the first construction as well, the blocks 8 being both 75 movable in the holder, they together with the bars 3 between them may be similarly shifted.

Other modes of applying the principle of my invention may be employed instead of 80 the one explained, change being made as regards the mechanism herein disclosed, provided the means stated by any of the following claims or the equivalent of such stated means be employed.

I therefore particularly point out and distinctly claim as my invention:—

1. In mechanism for casting type-bars, the combination with a holder having parallel sides; of matrix bars adapted to fit transversely in said holder, said bars having their sides parallel throughout and having their ends formed at an angle to their sides other than a right angle, whereby said bars slant at an angle to the sides of said holder, 95 the matrices on said bars lying parallel with, and being wholly contained between, the sides of said bars, substantially as described.

2. In mechanism for casting type-bars, the combination with a holder having parallel 100 sides, the ends of said holder being parallel with each other but inclined to such sides; of matrix bars adapted to fit transversely in said holder, said bars having their sides parallel throughout and having their ends 105 formed at an angle to their sides corresponding with the angle of said ends to such sides, the matrices on said bars lying parallel with and being wholly contained between the sides of said bars.

3. In mechanism for casting type-bars, the combination with a holder having parallel sides, the ends of said holder being parallel with each other but inclined to such sides and one such end being movable along said 115 holder; of detached matrix bars adapted to fit transversely in said holder, said bars having their sides parallel throughout and having their ends formed at an angle to their sides corresponding with the angle of said ends to such sides, the matrices on said bars lying parallel with and being wholly contained between the sides of said bars: and means for pressing said movable holder-end 120 inwardly against the adjacent bar.

4. In mechanism for casting type-bars, the combination with a holder having parallel sides, the ends of said holder being parallel

with each other but inclined to such sides, and such ends being furthermore movable along said holder; of detached matrix bars adapted to fit transversely in said holder, 5 said bars having their sides parallel throughout and having their ends formed at an angle to their sides corresponding with the angle of said ends to such sides, the matrices

on said bars lying parallel with and being wholly contained between the sides of said 10 bars.

Signed by me, this 16th day of May, 1911.

WILLIAM A. READE.
